PRINTING ATTACHMENT FOR EGG CARTON
HAND SET-UP MACHINELe Roy F. Carkhuff, Morris, Ill., assignor to Diamond
National Corporation, a corporation of Delaware

Filed Aug. 8, 1958, Ser. No. 753,944

7 Claims. (Cl. 93—37)

The present invention relates to a printing attachment for an egg carton hand set-up machine and more particularly to such an attachment that may be attached to such a machine without any modification of the structure thereof and which will work in conjunction with the working of the set-up machine.

In present day practice, one widely used type of egg carton is manufactured of relatively thin paperboard and is sent to an egg packer in knock-down or flat condition, this being done to conserve shipping space and to thus achieve economy. When these set-up type of cartons are received by the egg packer, they must be set up so that the eggs may be placed in them. There have been provided in the past three classes of devices for erecting the egg cartons: the first comprises simple implements with no moving parts; the second comprises simple hand or foot operated machines; the third comprises high speed power operated automatic machines.

While an egg packer has the second type, i.e., the hand operated type of machine, it has been necessary in the past to stamp a code indicating the date of packing and the plant at which the packing took place on the carton in a separate operation. Obviously, this has been time consuming and uneconomical.

Although there have been provided printing attachments for other types of machines, these attachments have been relatively complicated and have required the use of expensive and difficult to assemble parts.

An object of the present invention is to provide a printing attachment for an egg carton hand set up machine.

Another object of the present invention is the provision of a printing attachment that may be secured to an egg carton hand set-up machine without modification of the machine itself.

Yet another object of the present invention is to provide a printing attachment for an egg carton hand set-up machine that may be attached to the machine with only the simplest of tools that are readily available and easily manipulated, even by a person who is unskilled.

A further object of the present invention is the provision of a printing attachment for an egg carton hand set-up machine that is made of parts that are easy to make and are inexpensive.

A still further object of the present invention is to provide a printing attachment for a hand operated machine that will work in conjunction with the working of the existing parts of the machine.

Still another object of the present invention is the provision of a printing attachment for a hand operated machine that will permit the machine to operate in the normal manner and which will in no way slow down or interfere with the normal operation of the machine.

Other objects and the nature and advantages of the instant invention will be apparent from the following description taken in conjunction with the accompanying drawings, wherein:

Figs. 1 and 1a are front perspective views of opposite

2

ends of an egg carton hand set-up machine having the printing attachment of the present invention thereon;

Fig. 2 is a side elevation of the machine and attachments shown in Fig. 1;

Fig. 3 is an enlarged front elevation of one end of the set-up machine and the printing attachment, the printing attachment being in the rest position;

Fig. 4 is a view similar to Fig. 3, but with an egg carton in position on the machine and the parts in printing position;

Fig. 5 is an enlarged elevation from the rear of the set-up machine and showing the opposite side of the parts of Fig. 3 in rest position;

Fig. 6 is a view similar to Fig. 5, but showing an egg carton on the set-up machine from the rear of the machine and opposite the parts of Fig. 4 in printing position.

Referring now to the drawings, wherein like reference characters are used to designate like or corresponding parts throughout the several views, there is shown in Fig. 1 an egg carton hand set-up machine 10 comprising a frame 11 having upstanding ends 12. In the ends 12 there is journaled a longitudinally extending operating shaft 13 to which is secured an arm 14 that pivotally carries at its outer end an egg carton bottom deflecting and manipulating blade 16. A coil spring 17 encircles the shaft 13 at one end thereof and has one of its ends attached thereto and the other of its ends attached to the adjacent end 12 of the frame 11. On the end of shaft 13 opposite to spring 17 there is secured a rocker member 18 having a cam surface 19 thereon and the handle 21 attached thereto at its outer end.

Extending from the outside of the right hand end member 12 is a support 22 which carries therein a lever 23 mounted for pivotal movement, the upper end of the lever 23 carrying a cam follower 24 for engagement with the cam surface 19 and having at the lower end thereof a pusher face 26. Pusher face 26 acts on a reciprocable rod 27 that acts, through mechanisms not here pertinent, to cause swinging movement of the swingable leaves 28.

The swingable leaves 28 will rotate to the position shown in Figs. 4 and 6 upon downward movement of the handle 21.

Rising upwardly from the frame 11 and generally adjacent the swingable leaves 28 are a plurality of fixed leaves 29. Finally, on the right hand end 12 of the frame 11 there are two upstanding ears 31 and 32 between which is a slot 33 that receives an outstanding ear 34 of the blade 16 and thus guides it downwardly.

The parts above described are generally similar in construction and operation to the egg carton hand set-up machine described in Martin Burger Patent No. 2,668,482, issued February 9, 1954. With such a machine, it is only necessary to open up an egg carton so that it is in generally tubular condition, with an upstanding flap, and then to place this carton on the set-up machine and pull the handle downwardly. This will cause the swingable leaves to swing to upright position, and to carry the egg carton cross partitions also into upright position. Also, the blade 16 will descend to "tuck" the bottom to form the well known V-bottom carton. Thereafter, upon release of the handle, the spring will return the parts into the rest position, which is the position shown in Fig. 1.

A printing attachment 40 comprises a frame 41 that is attached to an end 12 of the frame 11 of the set-up machine by a pair of bolts 42 that extend through the frame 41 on either side of the end 12 and are anchored in the bar 43. This construction is seen in Fig. 2, where there may also be seen the edge of a plate 44 that may be integral with plate 41 and is positioned at right angles thereto, a plate 46 being in turn attached to the plate

44. Plate 44 carries a forwardly extending pin 47, and plate 46 has secured thereto a downwardly facing ink pad 48, two screws being used to secure the ink pad 48 to the plate 46.

Secured as by soldering or welding to the frame 41 is a horizontal transversely extending tube 49, this tube serving as a journal for a shaft 50. The tubed shaft 50 has at its front end an offset portion 51 on which is rotatably carried a type carrier 52 having an integral trip lever 53 that is furcated to provide the furcations 54 and 56 between which extends the pin 47.

In Fig. 5, there may be seen the end 12 of the frame 11, the coil spring 17 and the shaft 13 that is journaled in the end 12. There may also be seen the tube 49 and the back end of the shaft 50, this back end being angled.

Attached to the shaft 13 by an integral collar 57 that may be opened or closed by a wing nut 58 is a lever 59 that extends parallel to the shaft 13, thence outwardly, and finally parallel again to the shaft 13. This lever, which may be referred to as the operating lever, has connected to the free end thereof, a spring 55, the other end of which is connected to the angled back end of the shaft 50. It will be understood that when shaft 13 is rotated, operating lever 59 will also be rotated so that its free end swings in an arc about the axis of the shaft 13.

In operation, and referring first to Figs. 5 and 6, when the handle 21 is moved downwardly the shaft 13 will be rotated and this will move the blade 16 downwardly as well as cause swinging movement of the swingable leaves 28 by virtue of the actuation of lever 23 and cam 34. Simultaneously, operating lever 59 will be moved in an arc from the position shown in Fig. 5 to that shown in Fig. 6, and it may be seen that once the free end of operating lever 59 has passed on the upper side of a line drawn from the connection of spring 55 with the back end of shaft 50, and the axis of shaft 50 in the tube 49, the pull of the spring can take effect on the left hand side of this line, as seen in Fig. 5, and it will cause the shaft 50 to turn clockwise as seen in Fig. 5 and to thus assume the position shown in Fig. 6.

Referring now to Figs. 3 and 4, when the parts are in the rest position as shown in Fig. 3, the type in the type carrier 52 will be pressed against the ink pad 48, and when the tubed shaft 50 is rotated as above described, the offset portion 51 will travel in a counterclockwise direction as seen in Figs. 3 and 4 through an arc about the axis of tubed shaft 50. It will be understood that the apparent differences in direction of rotation of tubed shaft 50 are due to the fact that the descriptions of this rotation have been taken from the back and front ends thereof respectively. As the type carrier 52 is moved downwardly and to the right, from the Fig. 3 to the Fig. 4 position, it will be caused to rotate on the offset portion 51 because of the engagement of the pin 47 with the furcations 54 and 56 of the trip lever 53; this will cause the plane of the type face to move from a position parallel to the surface of the ink pad 48 to a position in which it is parallel to the end cross partition of an egg carton positioned in the hand set-up machines, as is shown in Figs. 4 and 6.

Upon release of handle 21, the spring 17 will cause the shaft 13 to rotate back to the rest position, and this will in turn carry the operating lever 59 from the position shown in Fig. 6 back to the position shown in Fig. 5, and during this movement the spring 55 will cause tubed shaft 50 to rotate in the opposite direction to that above described and this will in turn return the type carrier 52 to its rest position shown in Fig. 3 wherein the type comes into contact with the surface of ink pad 48 to receive ink therefrom and to thus be ready for the next operation.

It will thus be seen that there has been provided a printing attachment for an egg carton hand set-up machine that may readily be attached to the machine simply

by attaching the operating lever 59 to shaft 13 by means of the easily handled collar 57 and wing nut 58, and by attaching the frame 41 by the bolts 42 and bar 43. It may also be seen that the printing attachment may readily use standard rubber type that is readily available and inexpensive and that the parts of the printing attachment are either readily procurable or are made from plates and rods that are readily shaped on a punch press or on a press brake. Hence, it will be understood that these parts are all relatively easy to make and are quite inexpensive. Also, it will be noted that the securing of the printing attachment to the egg carton hand set-up machine requires no modification whatsoever to the machine.

It will be obvious to those skilled in the art that various changes may be made without departing from the spirit of the invention and therefore the invention is not limited to what is shown in the drawings and described in the specification but only as indicated in the appended claims.

What is claimed is:

1. In combination; a machine having a frame, a longitudinally extending operating shaft journaled therein, and means to rotate said shaft including a hand manipulable operating handle; and a printing attachment for said machine comprising a frame secured to the frame of the machine, a tube carried by said frame and extending transversely of said operating shaft, a shaft in said tube having the back end thereof angled to form a lever, an operating lever attached at one end to the operating shaft and extending outwardly from said operating shaft and then parallel thereto, a spring connected to the free end of said operating lever and to the angled end of said tubed shaft, whereby upon movement of said handle said tubed shaft will be rotated, the front end of said tubed shaft being offset, a type carrier rotatably mounted on the offset portion of said tubed shaft and having a furcated trip lever integral therewith, a pin carried by said attachment frame and extending between the furcations of said lever, and an ink pad carried by said attachment frame, said type carrier being carried by said offset portion of said tubed shaft and rotated by said pin upon rotation of said tubed shaft from a rest position in which the type is against the ink pad to a printing position in said machine.

2. In combination; a machine having a frame, a longitudinally extending operating shaft journaled therein; means for operating said shaft; and a printing attachment for said machine comprising a frame secured to the frame of the machine, a tube carried by said attachment frame and extending transversely of said operating shaft, a shaft in said tube having the back end thereof angled to form a lever, an operating lever attached at one end to the operating shaft and extending outwardly from said operating shaft and then parallel thereto, a spring connected to the free end of said operating lever and to the angled end of said tubed shaft, whereby upon rotation of said operating shaft said tubed shaft will be rotated, the front end of said tubed shaft being offset, a type carrier rotatably mounted on the offset portion of said tubed shaft and having a furcated trip lever integral therewith, a pin carried by said attachment frame and extending between the furcations of said lever, and an ink pad carried by said attachment frame, said type carrier being carried by said offset portion of said tubed shaft and rotated by said pin upon rotation of said tubed shaft from a rest position in which the type is against the ink pad to a printing position in which said type strikes against a work piece in position on said machine.

3. In combination, a machine having a frame, a longitudinally extending operating shaft journaled therein; means for operating said shaft; and a printing attachment for said machine comprising a frame secured to the frame of the machine, a tube carried by said attachment

frame and extending transversely of said operating shaft, a shaft in said tube, means connected to said operating shaft and said tubed shaft for rotating said tubed shaft upon rotation of said operating shaft, the front end of said tubed shaft being offset, a type carrier rotatably mounted on the offset portion of said tubed shaft and having a furcated trip lever integral therewith, a pin carried by said attachment frame and extending between the furcations of said lever, and an ink pad carried by said attachment frame, said type carrier being carried by said offset portion of said tubed shaft and rotated by said pin upon rotation of said tubed shaft from a rest position in which the type is against the ink pad to a printing position in which said type strikes against a work piece in position on said machine.

4. In combination, a machine having a frame, a longitudinally extending operating shaft journaled therein; means for operating said shaft; and a printing attachment for said machine comprising a frame secured to the frame of the machine, a shaft carried by said attachment frame transversely of said operating shaft, means connected to said shafts to cause said attachment shaft to rotate upon rotation of said operating shaft, the front end of said attachment shaft being offset, a type carrier rotatably mounted on the offset portion of said attachment shaft and having a furcated trip lever integral therewith, a pin carried by said attachment frame and extending between the furcations of said lever and an ink pad carried by said attachment frame, said type carrier being carried by said offset portion of said tubed shaft and rotated by said pin upon rotation of said tubed shaft from a rest position in which the type is against the ink pad to a printing position in which said type strikes against a work piece in position on said machine.

5. In combination; a machine having a frame, a longitudinally extending operating shaft journaled therein; means for operating said shaft; and a printing attachment for said machine comprising a frame secured to the frame of the machine, a tube carried by said attachment frame and extending transversely of said operating shaft, a shaft in said tube having the back end thereof angled to form a lever, an operating lever attached at one end to the operating shaft and extending outwardly from said operating shaft and then parallel thereto, a spring connected to the free end of said operating lever and to the angled end of said tubed shaft, whereby upon rotation of said operating shaft said tubed shaft will be rotated, the front end of said tubed shaft being offset, a type carrier rotatably mounted on the offset portion of said tubed shaft, an ink pad carried by said attachment frame, and means operatively connected to said type carrier to cause said carrier to rotate from a

rest position in which the type is against the ink pad to a printing position in which said type strikes against a work piece in position on said machine.

6. In combination, a machine having a frame, a longitudinally extending oscillatable operating shaft journaled therein; means for operating said shaft; and a printing attachment for said machine comprising a frame secured to the frame of the machine, a shaft carried by said attachment frame transversely of said operating shaft, means connected to said shafts to cause said attachment shaft to oscillate upon oscillation of said operating shaft, the front end of said attachment shaft being offset, a type carrier rotatably mounted on the offset portion of said attachment shaft, an ink pad carried by said attachment frame, and means operatively connected to said type carrier to cause said carrier to rotate from a rest position in which the type is against the ink pad to a printing position in which said type strikes against a work piece in position on said machine.

7. In combination; a machine having a frame, a longitudinally extending operating shaft journaled therein, and means to rotate said shaft including an operating handle; and a printing attachment for said machine comprising a frame secured to the frame of the machine, a tube carried by said frame and extending transversely of said operating shaft, a shaft in said tube having the back end thereof angled to form a lever, an operating lever attached by an integral split collar at one end thereof to the operating shaft and extending outwardly from said operating shaft and then parallel thereto, a spring connected to the free end of said operating lever and to the angled end of said tubed shaft, whereby upon movement of said handle said tubed shaft will be rotated, the front end of said tubed shaft being offset, a type carrier rotatably mounted on the offset portion of said tubed shaft and having a furcated trip lever integral therewith, a pin carried by said attachment frame and extending between the furcations of said lever, and an ink pad carried by said attachment frame, said type carrier being carried by said offset portion of said tubed shaft and rotated by said pin upon rotation of said tubed shaft from a rest position in which the type is against the ink pad to a printing position on said machine.
